UNITED STATES PATENT OFFICE.

CHARLES A. BRECKENRIDGE, OF MERIDEN, CONNECTICUT.

DESIGN FOR A BADGE OR PICTURE-FRAME.

SPECIFICATION forming part of Design No. 17,918, dated December 6, 1887.

Application filed October 28, 1887. Serial No. 253,675. Term of patent 3½ years.

To all whom it may concern:

Be it known that I, CHARLES A. BRECKENRIDGE, a citizen of the United States, residing at Meriden, in the county of New Haven and State of Connecticut, have invented and produced a new and original Design for Miniature Picture-Frames; and I do declare the following to be a full, clear, and exact description of the same, reference being had to the accompanying specification, forming a part thereof.

My design for badges or miniature picture-frames is shown in the accompanying drawings, wherein Figure 1 is a view in perspective of my invention, and Fig. 2 is a vertical cross-sectional view.

The nature of my design consists in a badge or picture-frame of the form of a miniature canteen, A, the outer front cloth or felt covering, a, of which is provided with an opening,

a', in which is placed a miniature picture, a'', and between the front and rear coverings projects a continuous flange, a², as shown. The upper portion of the canteen A has a neck, a³, and at its sides it has two hooks or eyes, a⁴.

I claim as my invention—

The design for badges or picture-frames herein described, and shown in the accompanying drawings, consisting of a miniature canteen having outer coverings, one of which is provided with a circular opening, the upper neck, and the hooks or eyes, as set forth.

In testimony whereof I affix my signature in presence of two witnesses.

CHARLES A. BRECKENRIDGE.
